UNITED STATES PATENT OFFICE

2,001,398

AIR DEFLECTOR AND WATER CIRCULATOR

Alfred W. Ravening, West Springfield, Mass.

Application April 4, 1933, Serial No. 664,406

5 Claims. (Cl. 122—4)

My invention relates to an air deflector and water circulator for coal burning heaters or furnaces for boilers and the like, and it has for its object to provide a device of this character which 5 may be placed in the bed of coals and which will facilitate combustion of the fuel.

A further object of my invention is to provide a device of this character which will facilitate the heating of water to the maximum degree 10 without waste of fuel.

A still further object is to provide a device of this character which may be cheaply and readily constructed and can be produced at a relatively 15 low cost.

15 With these and other objects in view, my invention will be readily understood upon reference to the accompanying drawing in which:

Figure 1 is a sectional view of a suitable boiler with my invention applied thereto;

20 Figure 2 is a vertical section of my device removed or detached from the boiler;

Figure 3 is a sectional plan view on line 3—3 of Figure 2;

25 Figure 4 is a sectional plan view on line 4—4 of Figure 2.

Upon referring to the drawing, A designates a boiler of any desired construction having a suitable support B and a grate C.

Located above the grate is my improved air deflector and water circulating device D. This device may be centrally located if desired and sufficiently high enough above the plane of the grate to provide adequate clearance. This improved air deflector and water circulator may be made 35 in any suitable manner, but I prefer to form it from a small cylinder like casting which may be suitably cored to provide upper and lower compartments 1 and 2. The upper compartment is for high temperature water and the lower compartment is for low temperature water.

40 These two compartments may be connected together by suitable tubes or passages 3. While I have obtained excellent results from only two of these passages, it is obvious that additional ones may be employed if desired.

45 The water passes from the lower compartment 2 through these passages 3 into the upper compartment and the high temperature water is then let off through the pipe or passage 4. Water is supplied to the compartment 2, preferably at the bottom thereof, by means of the pipe or passage 5. The chamber 2 is preferably annular, having the central air passage 7, while the upper compartment 1 may have a flat bottom 8 with a

domed top 9. The upper compartment 1 may be greater in diameter than the compartment 2.

While these compartments are shown on the outside as cylindrical in shape, it is obvious that they may be made of other contour.

5 It will be noted that the inlet and outlet pipes 4 and 5 serve to support the casting and are located substantially at the center of the fire pot. Low temperature water will enter through the pipe 5 into the lower compartment 2 where it 10 is suitably heated and the high temperature water rises through the passages 3 into compartment 1 where an increased heating is given the water. The water then passes out through the central outlet pipe 4 and may be conducted into 15 the water compartment of the boiler to just below the normal water line of the boiler, thus preserving the thermosyphon effect.

The air will enter the passageway 7 from beneath the grate and will flow upwardly against 20 the bottom plate 8 of the upper compartment 1, and will be deflected radially in all directions, thus supplying air at the approximate center of the burning fuel and tending to promote perfect combustion.

25 The upper compartment 1 being of larger diameter than the lower compartment 2, the passageway 7 will be kept open and clear from waste fuel.

In use, my improved air deflector and water 30 circulator is located approximately at the center of the fire pot above the grate. The device is embedded in the fuel above the grate and may be entirely covered thereby and is practically submerged at all times in the incandescent fuel. The 35 water entering the pipe 5, after being heated in the lower compartment, rises to the upper compartment for a final heat treatment and then is conducted downwardly through the pipe 4 to the boiler, as before stated. The air entering the central passage 7 is deflected at right angles by the bottom wall of the upper compartment and supplies additional air to promote perfect combustion at the upper part of the fuel bed, thus eliminating soot to a minimum, reducing the ash content, and insuring perfect combustion.

40 What is claimed is:

1. A combined air deflector and water circulator comprising a lower compartment having an air passageway therethrough, an upper water 50 compartment spaced but a short distance from the lower compartment, connecting columns between the upper and lower compartments for supplying water from the lower compartment to the upper compartment, a discharge conduit for the 55

upper compartment disposed in the air passage-way of the lower compartment, and means for supplying water to the lower compartment.

2. A combined air deflector and water circulator comprising a lower water compartment having a central air passage therethrough, an upper water compartment spaced but a short distance from the lower compartment, spaced connecting columns between the upper and lower compartments for supplying water from the lower compartment to the upper compartment, a discharge outlet for the upper compartment disposed within the central air passage of the lower compartment, and means for supplying water to the lower compartment.

3. A combined air deflector and water circulator comprising an annular lower water compartment having an air passage therethrough, an upper water compartment spaced a short distance above the lower compartment and disposed over the air passage of the lower compartment to deflect up coming air radially, and water columns connecting the upper and lower compartments.

4. A combined air deflector and water circulator comprising a lower water compartment having a central air passage therethrough, a

spaced upper water compartment disposed a short distance above the lower water compartment and over the central air passage, the upper compartment being larger in diameter so that its edges overhang the edges of the lower compartment to prevent accumulation of residue in the central air passage, connections between the upper and lower compartments for supplying water from the lower to the upper compartment, and a discharge pipe for the upper compartment.

5. A combined air deflector and water circulator comprising an annular lower water compartment vertically disposed, defining a central air passage therein, a water inlet for the lower compartment, an upper compartment spaced from the lower compartment and horizontally disposed, said lower compartment being located over the central air passage to deflect rising air currents outwardly at an angle to the central air passage, water columns connecting the upper and lower compartments for conducting water to the upper compartment from the lower compartment, and an outlet for the upper compartment extending downwardly through the central air passage.

ALFRED W. RAVENING.
